PORTRABLE LAMP

Stephen W. Morris, 1300 Fernside Blvd.,
Alameda, Calif. 94501

Filed Dec. 11, 1967, Ser. No. 9,732

Term of patent 14 years

(Cl. D48—20)

Fig. 1.

Fig. 2.

FIG. 3.

FIG. 4.

I claim:

The ornamental design for a portable lamp, as shown and described.
